UNITED STATES PATENT OFFICE.

GEORGE KOFFSKEY, OF NEW ORLEANS, LOUISIANA.

NAUTICAL INSTRUMENT.

1,245,355.

Specification of Letters Patent.

Patented Nov. 6, 1917.

Application filed August 5, 1916, Serial No. 113,258. Renewed October 2, 1917. Serial No. 194,413.

To all whom it may concern:

Be it known that I, GEORGE KOFFSKEY, a citizen of the United States, and a resident of New Orleans, in the parish of Orleans and State of Louisiana, have invented a new and Improved Nautical Instrument, of which the following is a full, clear, and exact description.

My invention relates to an instrument for solving mechanically the astronomical triangle whereby the instrument is particularly adaptable for navigation purposes.

An object of the invention is to provide a simple, convenient and inexpensive apparatus for solving mechanically the astronomical triangle.

Another object of the invention is to provide an instrument by which the sun gives the position of the instrument at any hour of the day, consequently the position of a vessel at sea may be determined, the determination of the exact location depending on the accuracy of the elements constituting the device.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a perspective front elevation of the instrument, the hand plate not being shown;

Fig. 2 is a rear elevation;

Fig. 3 is an end elevation without the end plate;

Fig. 4 is a top view of the instrument the hand plate being shown in use; and

Fig. 5 is a section on line 5—5, Fig. 4.

Referring to the drawings, 6 and 7 are two plates forming circular sectors hinged on their radial line through the medium of a bolt 8. The end of the bolt extends from a carrier or support 9, in the shape of a plate, having two portions 10 and 11 offset from each other lying in parallel planes and both disposed at right angles to the bolt 8 on which the plates 6 and 7 are hinged. The reason for offsetting one portion of the plane from the other is to accommodate the larger sector formed by the plate 7.

The plates 6 and 7 have an enlargement 12 at the end bearing against the corresponding portions of the support 9. The portion 10 of the support 9 has a circular slot 13 in register with the enlargement 12 of the plate 6, the center of which slot is in the axis of the bolt 8. The portion 11 of the support 9 has also a circular slot 13 in register with the enlargement 12 of the plate 7, the center of which slot is in the axis of the bolt 8. The portions 10 and 11 of the support 9 are each graduated along their slots, the zero of each lying in a common plane passing through the axis of the hinge. The divisions of said scales are such as to read to 30' of an arc. A vernier 13' is connected to the enlarged portion 12 of each sector to coöperate with the corresponding scale on the support. The vernier has an additional guiding pin in the groove to maintain the same in proper relation to the corresponding scale during the displacement of the plate.

To increase the stability of the device, the bolt 8 is provided with an additional bearing 14 remote from the support 9 and which is braced to said support 9 by rods 15 extending from the bearing 14 to the support. The displacement of either plate 6 or 7 on its hinge is indicated by the scales on the portions 10 and 11 of the support 9, the angle indicated by said scales being formed by either of the plates with the plane passing through the axis of the hinge and the zero division of said scales. The arcuate edge of the plates 6 and 7 is divided into degrees to read to 30', the zero of said scales being on the axis of the hinge. Each plate has an arcuated bridge 16 concentric with the arcuated edge of the plate. Each bridge constitutes a guide for a vernier 17 coöperating with the corresponding scale. Each of the verniers 17 has extensions 18 at each end thereof which engage the arcuated edge of the corresponding plate. These extensions form additional guides for the verniers and insure a more exact reading.

A hand plate 19 coöperates with the plates 6 and 7. Said hand plate is in the shape of a circular segment having a handle 20 for facilitating the manipulation thereof. The concave edge of the segment is subdivided into degrees to read to 30'. At zero of the scale, which lies in close proximity to the end of the plate, there is a pointer 21 central with the zero division and for which

- there are niches 22 in the extensions 18 of the verniers 17. An arcuated bridge 23 is provided on the hand plate 19 to be concentric with the concave edge of the hand plate.
- 5 This bridge constitutes a guide for a vernier 24, which vernier has a pointer 25 at its zero division also adapted to enter the niche 22 provided in the extension 18 of the verniers 17 (see Fig. 5).
- 10 To find the altitude of places at the time of observation, determine the apparent altitude of sun at any hour of the day and correct it for true latitude, also note the apparent time of observation. Set the plates 15 6 and 7 to the hour angle of observation. On plate 7 set the vernier to the polar distance of the day and hour, taking the declination from the nautical almanac. Set the vernier on hand plate 19 to the observed 20 altitude of the sun corrected. Place the pointer of the vernier 24 on the hand plate into a niche of the extension of the vernier on the plate 7, then move the vernier on plate 6 to bring the niche of the proper extension thereof into engagement with the pointer of the hand plate. The angle read on plate 6 will be the co-latitude, and this subtracted from 90 gives the latitude of place at the time of observation.
- 25 The latitude may also be determined in the following manner. Take the compass azimuth of the sun and correct for error to get the true bearing of the sun. Set plates 30 6 and 7 to this angle. Place the vernier 17 on plate 6 to the co-altitude of sun corrected. For this purpose observe the apparent altitude of the sun and make the necessary corrections to get the correct altitude. Move the vernier 24 on the hand plate 19 to ex-
- 35 40 press the polar distance for the day and hour, taking the declination of the sun from the nautical almanac. Place the pointer 21 of the hand plate into a niche of an extension 18 of the vernier 17 on the plate 6, then move the vernier 17 on plate 7 and bring the proper niche of an extension 18 into engagement with a pointer 25 of the vernier 24 on the hand plate. The co-latitude is then found on the plate 7, which subtracted from 50 90 will give the latitude.
- 45 50 Knowing the time of sunrise, the hours, minutes and seconds of time are changed to degrees, minutes and seconds of arc. The derived degrees, minutes and seconds of arc are set on plate 7 by means of the vernier 17. Then the declination of sun for day and hour is taken from a nautical almanac and this is set on plate 6. The plates 6 and 7 are then moved to 45° on the support so that the angle included by the two plates is 90° . The pointer 21 of the hand plate 19 is then brought into a niche of an extension 18 of either of the verniers 17. The vernier 24 on the hand plate is then moved to bring 55 60 65 70 the pointer 25 thereof into the niche of the

extension of the other vernier. If the pointer 21 is engaged in the left-hand extension of a vernier, the pointer 25 is also engaged in the left-hand extension of the other vernier so that the reading will be between the centers of the two verniers. The result obtained on the hand plate in degrees, minutes and seconds gives the co-true bearing of the sun.

Having found the true bearing of the sun, 75 the result is set on plate 7, the declination of sun being indicated on plate 6. The vernier on hand plate 19 is then set to the converted time of sunrise. By placing the pointer 21 of hand plate into a niche of the extension 18 of a vernier, and moving the other plate on its hinge to bring the corresponding niche of the extension into engagement with the pointer 25 of the vernier 24, the included angle made by the plates 6 and 80 85 90 95 100 105 110 115 120 125 130 135 140 145 150 155 160 165 170 175 180 185 190 195 200 205 210 215 220 225 230 - pair of hinged circular sectors each having divisions at the curved edge thereof for indicating angles of which one side is the axis of the hinge, a carrier engaging the pivot of 5 the sector's hinge, said carrier having divisions for indicating the angular relation between the sectors, and a member for indicating the angular relation between any two divisions of the two sectors.
- 10 5. A nautical instrument comprising a support, a bolt projecting from said support, a pair of circular sectors hinged to the bolt on a radial line, said support having circular slots the center of which is in 15 the axis of the bolt, each of said sectors having means engaging the slots, said support having divisions at the slot for indicating the angular relation between the sectors, each of said sectors having divisions 20 for indicating angles thereupon of which one side is in the axis of the bolt, and a plate having means for indicating angles thereupon for indicating the angular relation between any two divisions of the two 25 sectors.
6. A nautical instrument comprising a pair of hinged plates each having divisions to indicate angles thereupon of which one side is in the axis of the hinge, a support 30 for the plates having means for indicating the angular relation between the hinged plates, and a plate having a fixed member and a movable member for indicating the angular relation between any two divisions 35 of the two plates.
7. A nautical instrument comprising a support, a bolt projecting at right angles to the support, a pair of circular sectors hinged to the bolt on their radial lines, said sectors 40 having means engaging the support, said support having divisions for indicating the angular relation of the sectors, a movable member on each sector for indicating angles thereupon of which one side is in the axis 45 of the bolt, a circular segment having a fixed member adapted to engage either of the movable members on the sector, and a movable member on said circular segment for indicating angles thereupon between the 50 fixed and the movable member, said movable member adapted to engage either of

the movable members on the sector whereby the angular relation between said movable members and the sector may be determined.

8. A nautical instrument comprising a 55 pair of hinged circular sectors, a support for said sectors having means for indicating the angular relation between the sectors, a movable member on each of said sectors for indicating angles thereupon of which one 60 side is in the axis of the hinge, a circular segment having a fixed member adapted to engage either of the movable members of the sector, and a movable member on said circular segment for indicating angles 65 thereupon of which one side is the fixed member of said segment and the other side the movable member, said movable member being adapted to engage either of the movable members of the sectors whereby the 70 angular relation between the movable members on the sectors may be determined.

9. A nautical instrument comprising a support, a pair of hinged circular sectors secured to the support with the axis of the 75 hinge perpendicular to said support, angular divisions on said sectors, movable verniers coöperating with the angular divisions for reading angles thereupon, one side of which angles is in the axis of the hinge, said 80 support having an arcuated groove the center of curvature of which groove is in the axis of the sector's hinge, a vernier associated with each sector and in engagement with the groove, angular divisions on the 85 support disposed to coöperate with the last-mentioned verniers whereby the angular relation between the sectors may be read, a circular segment having angular divisions thereupon, a fixed pointer on said segment 90 extending from the zero division on said segment, and a vernier movable on said circular segment for reading the angular divisions on said segment, said vernier having a pointer extending from the division of the 95 vernier, said verniers on the sectors having means for receiving the pointer of the segment and the vernier thereupon whereby the angular relation between the verniers on the sectors may be determined.

GEORGE KOFFSKEY.
